ROBERT K. DAWSON, OF AKRON, NEW YORK.

FURNACE.

Application filed October 2, 1926, Serial No. 139,188, and in Canada January 30, 1925.

This invention relates to furnaces, and more particularly to hot air furnaces of the type commonly used for heating buildings.

The objects of this invention are to construct a furnace of this kind mainly of sheet metal, so that a lighter, more efficient and less expensive furnace is produced; also to provide a furnace of this kind with means for increasing the flow of air through the furnace; also to provide improved means for arranging the feed and ash door openings on the furnace; also to provide improved means for supporting the fire pot in the furnace; also to provide means of improved construction for increasing the radiation of heat from the combustion chamber into the air space surrounding the same; also to provide improved means for mounting the grate on the furnace and also to improve the construction of furnaces of this kind in the other respects hereinafter specified.

In the accompanying drawings:

Fig. 1 is an elevation, partly in section, of a furnace embodying the invention.

Fig. 2 is a sectional plan view thereof, showing the top of the combustion chamber.

Fig. 3 is a central, sectional elevation thereof on an enlarged scale on line 3—3, Fig. 2.

Fig. 4 is a fragmentary, sectional plan view thereof on line 4—4, Fig. 3.

Fig. 5 is a fragmentary, perspective view of a part of a shell of the combustion chamber showing portions of the shell bent outwardly to form the sides of the door opening.

Fig. 6 is a fragmentary, sectional elevation thereof on line 6—6, Fig. 2, showing the means for increasing the radiating capacity of the combustion chamber.

Fig. 7 is a front elevation of the heater or heating element detached from the furnace, the feed and ash doors being omitted.

Fig. 8 is a front elevation of the lower part of the heater showing the feed and ash doors arranged thereon.

Fig. 9 is a sectional, top plan view of the furnace on line 9—9, Fig. 3.

Fig. 10 is a fragmentary, sectional plan view of the heater or heating element of the furnace on line 10—10, Fig. 3.

Fig. 11 is a fragmentary, sectional elevation thereof on an enlarged scale on line 11—11, Fig. 3.

Fig. 12 is a perspective view of a section of the refractory lining of the heater.

The furnace includes the usual heater or heating element comprising a combustion chamber A, a fire pot B, a grate C and an ash pit D, and the heater is surrounded by a shell E which is spaced from the walls of the heater and is provided near the lower portion thereof with a cold air inlet e. F represents the smoke pipe or duct of the heating element. The upper portion of the outer shell or casing E is intended to be provided with the usual pipes or ducts for conducting warm air to the rooms of a building, these pipes or ducts not being shown in the drawings. It will be understood, however, that it is not intended to limit this invention to a furnace of this type since the invention may be used in connection with furnaces of the pipeless kind, in which case another shell would be provided, which would form with the shell E a downward passage for the cold air. The shell E may be of any suitable or desired construction.

Heretofore the heaters or heating elements of furnaces of this kind have been constructed mainly of cast metal. In accordance with this invention, however, the shell or housing of the heater is made of sheet metal which is bent into substantially cylindrical form, a shell 15 being shown in the construction illustrated, which is formed of a single sheet of metal, the edges of which are suitably secured together, for example, by welding as at 16. A ring 17 may be suitably secured to the lower edge of the cylindrical shell 15, and a plate or disk 18 closes the lower end of the cylindrical shell and forms the floor or bottom of the ash pit D. The upper end of the shell 15 of the heater is closed by means of a dome 20 which is preferably also made of sheet metal, and the edges of this dome preferably extend slightly beyond the periphery of the shell 15 and are welded to the shell as shown at 21, to insure a tight joint between the dome and the shell. Other means for securing the dome to the shell may, however, be used, if desired. The dome preferably is also provided with a plurality of corrugations or annular bends 22 which may be of any suitable shape and which serve the purpose of preventing buckling or deformation and

possible separation of the same from the cylindrical wall 15 during the expansion and contraction of the dome when subjected to different temperatures. These corrugations 5 also increase the radiation of heat from the dome.

The connection between the combustion chamber A in the upper portion of the shell 15 and the flue F for the exhaust gases 10 is effected by means of a down draft passage G, which is preferably formed of sheet metal and is spaced from the heater wall 15 to allow air to pass between the passage or radiator G and the heater. The passage or 15 radiator G is of considerable width and is curved or formed substantially concentric with the heater wall 15. A short pipe or flue 24 in the form of a flanged ring connects the passage or radiator G with a hole 20 25 in the cylindrical heater wall 15, and this pipe or flue 24 also serves to support the passage or radiator G from the heater wall. A baffle 26 is preferably arranged in the lower portion of the passage or radiator 25 G to cause the products of combustion to pass over the bottom wall of the radiator G to increase the amount of heat extracted from the radiator G. The lower portion of 30 the passage or member G is provided with a hole or opening communicating with the flue or smoke duct F. By providing a downflow passage connecting the flue or smoke duct with the top of the combustion chamber instead of connecting the flue directly to the top of the combustion chamber, an increase in the efficiency of the heater is obtained, since a considerable portion of 35 the heat still remaining in the gases and products of combustion passing through the opening 25 in the shell 15 is radiated through the relatively thin sheet metal wall of the downflow passage G and thus assists in heating the air in the air space between the heater and the outer shell E of the furnace.

In order to further assist in the transmission of the heat from the walls of the combustion chamber to the air surrounding the combustion chamber and to accelerate the 40 upward flow of the air surrounding the combustion chamber, a plurality of radiating fins or channels may be arranged on the upper portion of the shell 15 around the combustion chamber A. In the construction shown, these fins or air flues 28 are substantially channel-shaped and the edges thereof are suitably secured to the outer face of the shell 15, thus forming a plurality of 45 passages open at their upper and lower ends through which air can pass. The outer walls of the channels 28 are preferably also constructed to admit air along the length of these channels or flues, a plurality of holes 29 being provided for this purpose in 50 the particular construction shown. These

radiating fins 28 conduct the heat from the shell 15 and greatly increase the radiating surface of the shell and thus increase the efficiency of the heater, since the air passing on both sides of the fins is heated, as 55 well as the air contacting with the outer face of the shell 15. It has also been found that the columns of air in the channels or air flues 28, due to the heat imparted thereto both by the wall 15 and the channels or flues 28, and to the fact that the air is free to rise without encountering the frictional resistance to flow by other air in the air space around the heater, rise with a greatly accelerated speed, and thus increase the 60 speed of flow of all of the air through the air space by a stack effect causing a more pronounced upward movement of the air between the furnace casing and the shell by an injector action of the air discharged by 65 the flues, which in turn increases greatly the efficiency of the furnace. The flow of air upwardly in these channels or fins has been found to be so rapid that a considerable suction was formed within the channels 70 when imperforate or closed channels were used, and consequently the flow of air in the flues or fins 28 and through the entire air space in the furnace was further accelerated by providing air admission openings in the fins or flues, such as the holes 29. It has been found that when the furnace is 75 in operation, air enters all of these holes and thus not only breaks the suction or partial vacuum in the channels or flues 28, but also increases the volume of air passing upwardly in these air flues or fins, as well as the circulation of air in the entire heating system. However, a very considerable increase in efficiency can be obtained by the 80 use of channels or flues 28 without holes or openings therein, though still greater efficiency is obtained with the holes or openings. Other forms of fins, channels or flues 85 may be used without departing from this 90 invention.

The door openings of the heater may be of any suitable or desired construction, those shown in the drawings being formed by cutting the metal of the shell 15 inwardly substantially at right angles to the longitudinal edges 16 of the shell before the longitudinal seam of the shell is made, and portions of the metal of the shell are then bent forwardly, as indicated at 32, Fig. 5, to form the sides of the door opening, this construction being 95 preferably used in forming both the openings for the feed and the ash pit doors. Metal plates 33 are then cut or shaped to cooperate with the top and bottom edges of the side portions 32 of the door openings and with the outer face of the shell 15 to form with the portions 32 outwardly extending openings, and these plates are preferably welded 100 at their edges.

40 represents door frames suitably secured to the forwardly projecting portions of the heater, and ash and feed doors 41 and 42 respectively are mounted in the usual manner on the door frame 40. By means of this arrangement, the sides of the door openings are integral with the shell 15 of the heater and the top and bottom plates 33 are welded to the shell and sides of the door openings 10 so that the escape of gases or products of combustion from the heater into the air space around the heater is prevented. Furthermore, this construction makes it possible to use top and bottom plates for all door openings which are identical in size and form and can all be formed by the same set of cutting dies.

In order to prevent the heat of the fire from burning through or otherwise damaging the relatively thin, sheet metal plate of which the cylindrical wall of the heater is formed, the portion of the cylindrical shell 15 surrounding the fire pot is preferably lined with or protected by a layer of fire brick, tile or other refractory substance. Means are, therefore, provided for suitably supporting the fire brick or refractory lining within the shell 15, and these means are preferably also adapted to support the grates C. 20 In the particular construction shown, the refractory material 44 is supported by a metal ledge or ring 45 which is of angle-shaped cross section and which is provided at intervals with lugs 46 adapted to be bolted or otherwise secured to the inner face of the shell 15. The upwardly extending flange of the angle-shaped portion of the supporting ledge or ring 45 is adapted to engage the inner face of the lower portion of the refractory lining 44 and thus serves to hold this lining against displacement toward the center of the heater while the shell 15 holds the lining against displacement in the opposite direction. The lining 44 in the construction 30 shown is formed in a plurality of arc-shaped sections adapted to be fitted into the shell 15 of the furnace, and some of the sections arranged adjacent to the feed door opening are slightly lower than the other sections so as to permit ready access from the feed door to the fire pot. It is also desirable that some circulation of air be provided for between the refractory lining 44 and the cylindrical shell 15, and for this purpose the several 40 arc-shaped portions of the lining 44 are provided with a plurality of upright, shallow recesses or depressions 47, see particularly Fig. 4, which are of sufficient size to permit air to pass between the refractory lining and the shell 15 and thus effect a cooling of the portion of the shell 15 adjacent to the fire pot. The air which is thus heated is discharged toward the fire through holes or apertures 48 in the lining connecting with the passages 47 therein, and this heated air

adds greatly to the efficiency of the combustion of the fuel. In order to insure a thorough heating of the air before the same is discharged from the holes 48, the several sections of the lining at the rear and side of the furnace are provided at their lower ends with outwardly extending flanges 47^a and the supporting ring 45 at these parts of the furnace extends into close proximity to the heater wall 15. At the front wall of the furnace the ring 45 is provided with recessed portions 45^a, and the lower flange of the sections of refractory material is omitted, so that air can enter the space between the refractory material and the heater wall 15 at the front of the furnace and circulate in the space 47, where the air becomes heated and from which space the heated air passes through the openings 48.

The grate C may be of any suitable construction, but is preferably in the form of a single piece grid having a plurality of openings or holes 49 therein through which air may pass upwardly to the fire and through which ashes may drop from the fire into the ash pit, and the central portion of the grate is preferably raised, as indicated at 50, to provide better distribution of air through the material in the fire pot to prevent the fire from burning too rapidly at the center of the fire pot. This grate, in the construction shown, is arranged within the ring 45 which supports the refractory lining, and the grate is preferably provided at opposite sides with pivots or trunnions 51, 100 preferably formed integral with the grate and adapted to rest on shelves or ledges 52 which are preferably formed integral with the lining supporting ring 45, see particularly Figs. 3 and 11. These shelves or ledges 52 are preferably long enough to permit the furnace to be shaken by moving the grate substantially about its center through a small arc of a circle. To facilitate the shaking of the furnace, an integral projection or arm 54 extends downwardly and forwardly from the grate C and is preferably suitably suspended on the furnace in such a manner as to permit a certain amount of lateral movement of the projecting arm 110 when the furnace is being shaken. Any means for supporting the arm 54 in such a manner as to enable the same to move laterally may be employed. In the construction shown, a ledge or bracket 55 is used which is secured on the lining supporting ring 45 and on which the arm 54 rests so as to permit the arm to be moved laterally to shake the ashes from the fire pot into the ash pit. The shaking of the grate may be effected in any desired manner, for example, by means of a lever 56 pivoted at 57 on a side of the furnace. A reciprocating bar 58 is slidably arranged in the front portion of the furnace and has at one end a forked connection 120 130

with the grate arm 54, and at the other end this bar is connected with the lever to be actuated thereby. During the ordinary shaking of the grate, the same receives a more or less rotary motion about its vertical axis, during which the trunnions 51 slide on the ledges or shelves 52, and this rotary motion is limited by the end of the forwardly extending arm 54 engaging stops 60, Fig. 8, which may be of any suitable construction and all shown in the drawings in the form of integral projections formed on the ash pit door. When it is desired to dump the fire or ash from the grate, the ash pit door 15 is opened and the upper end of the lever 56 is moved toward the furnace, which permits the projecting arm 54 to move off the end of the supporting ledge 55, whereupon the grate is free to swing about the trunnions 51, so that the front end of the grate can swing downwardly to permit the contents of the fire pot to fall forwardly into the ash pit. The grate can readily be replaced into its normal position by placing the arm 54 between the forked connection 59 and then laterally upon the ledge 55. A grate of any other construction may be provided, if desired.

The furnace described has the advantage that the heater is made of a shell of comparatively thin metal so that the heat of the fire may readily pass through this shell and into the air in the space surrounding the shell. Furthermore, the cost of production 30 of a furnace of this kind and the weight of the same is greatly reduced by using the comparatively light sheet metal shell 15 in place of the relatively heavy cast shells heretofore commonly employed. The lining or refractory material in the fire pot keeps the fire itself out of direct contact with the comparatively thin shell 15, and thereby avoids damage to this portion of the shell. A furnace of the construction described 35 furthermore has the advantage that the sheet metal, such for example as sheet steel or iron, is practically free from the pores that are common in cast iron, and consequently with a furnace of the kind shown 40 in the drawings, there is very little chance for gas or products of combustion to leak or pass from the heater into the hot air space surrounding the heater, so that the smell of gas frequently experienced in houses 45 heated by hot air furnaces is eliminated by means of this construction. Furthermore, the entire shell has only one longitudinal seam and another seam at the upper end thereof connecting the shell and dome, and when a welding process is used in connection with the making of these seams, they 50 can easily be made absolutely gas tight. The construction described also makes it possible to readily apply the radiating fins 55 described to the other face of the shell of

the heater, which feature adds greatly to the efficiency of the furnace. Because of the lightness of weight of the furnace, the same can be shipped and installed at a considerable saving of expense.

70

I claim as my invention:

1. In a furnace having an outer casing, a heater arranged in said casing and including a tubular shell within which combustion takes place, and a plurality of channel strips secured with their open faces approximately against the outer face of said shell to extend upwardly along the same, each strip being open at both ends to the space within said casing surrounding said shell and all spaced apart from one another laterally around said shell, whereby the air confined in the channel of each of said strips by the wall of said shell will be heated to a greater extent than the surrounding air in said casing and will have a stack effect causing a more pronounced upward movement of said surrounding air by the injector action of the air discharged by said flues.

2. In a furnace having an outer casing, a heater arranged in said casing and including a tubular shell within which combustion takes place, and a plurality of channel strips secured with their open faces approximately against the outer face of said shell to extend upwardly along the same, each strip being open at both ends to the space within said casing surrounding said shell and all spaced apart from one another laterally around said shell, whereby the air confined in the channel of each of said strips by the wall of said shell will be heated to a greater extent than the surrounding air in said casing and will have a stack effect causing a more pronounced upward movement of said surrounding air by the injector action of the air discharged by said flues, the flues formed by the channels and shell being in communication with said surrounding air at points intermediate their ends.

3. In a furnace having an outer casing, a heater arranged in said casing and including a tubular shell within which combustion takes place, and a plurality of channel strips secured with their open faces approximately against the outer face of said shell to extend upwardly along the same, each strip being open at both ends to the space within said casing surrounding said shell and all spaced apart from one another laterally around said shell, whereby the air confined in the channel of each of said strips by the wall of said shell will be heated to a greater extent than the surrounding air in said casing and will have a stack effect causing a more pronounced upward movement of said surrounding air by the injector action of the air discharged by said flues, said channel strips being apertured intermediate their ends to permit entrance to the rising

110

115

120

125

130

air columns therein of some surrounding air.

4. A furnace having an outer casing, a heater in said casing and forming with said casing a space for the medium to be heated, 5 a series of upright open ended channels secured to said heater with their open sides facing said heater and forming therewith passages for columns of the medium to be heated with openings at the sides of said 10 columns for admission thereto of the medium to be heated.

5. A furnace having an outer casing, a heater in said casing and forming with said casing a space for the medium to be heated, 15 a series of upright open ended channels secured to said heater with their open sides facing said heater and forming therewith passages for columns of the medium to be heated with openings at the sides of said 20 columns for admission thereto of the medium to be heated, each of said channels

having a plurality of apertures therein spaced apart along their length for the entrance to said passages of additional air.

6. A furnace having an outer casing, a 25 heater in said casing and forming with said casing a space for the medium to be heated, a series of upright open ended channels secured at spaced apart intervals to said heater and extending into the space containing said 30 medium to be heated and forming passages for the columns of said medium, said columns having a series of openings in the sides thereof for admission of the medium to be heated, said medium to be heated in said 35 space receiving heat from portions of said heater casing between said channels, the medium in said channels passing upwardly in said channels at an accelerated speed and increasing the upward velocity of all of the 40 medium enclosed in said space.

ROBERT K. DAWSON.
